Primary Examiner — Jonathan J Han(74) *Attorney, Agent, or Firm* — Shaddock Law Group, PC(57) **CLAIM**

The ornamental design for an overmolded firearm magazine, as shown and described.

DESCRIPTION

FIG. 1 is an upper, right side perspective view of an exemplary embodiment of an overmolded firearm magazine, showing my new design;

FIG. 2 is a right side view of the present invention;

FIG. 3 is a left side view of the present invention;

FIG. 4 is a rear view of the present invention;

FIG. 5 is a front view of the present invention;

FIG. 6 is a top view of the present invention; and,

FIG. 7 is a bottom view of the present invention.

The broken lines in the figures depict portions of the overmolded firearm magazine that form no part of the claimed design.
